UNITED STATES PATENT OFFICE.

ZACHARIAH F. JONES, OF SCOTTSVILLE, VIRGINIA.

FIRE ESCAPE.

Application filed March 14, 1927. Serial No. 175,363.

The invention relates to an improved fire escape of the portable, rope-friction type and the same has been especially designed for use to permit persons to escape through windows of a building, when elevators or stairways are inaccessible due to flames and smoke.

The principal object of the invention is to provide a fire escape of the class set forth which is rather simple and inexpensive, yet will be efficient, durable, and well adapted for use by the average person, without jeopardy.

In carrying out the above end, further aims are to provide a new and generally improved main body for the device; to provide new and improved friction-creating means; to provide novel means whereby the friction on the rope may be increased or diminished as occasion may demand; to make unique provision for normally housing the rope, yet permitting it to readily straighten out and descend to the ground when thrown out of a window; to provide an attachment whereby the fire escape may be used by painters or others working upon the exterior of a building, etc.

With the foregoing in view, the invention resides in the novel subject matter herein-after described and claimed, the description being supplemented by the accompanying drawings.

Fig. 1 is a front elevation of the device suspended in readiness for use, at a window opening.

Fig. 2 is a vertical section on line 2—2 of Fig. 1, showing the device in use.

Fig. 3 is an enlarged vertical sectional view partly in elevation, cut in a plane between the front and rear sides of the device.

Fig. 4 is a vertical section on line 4—4 of Fig. 3.

Fig. 5 is a small elevation illustrating the manner in which the device may be mounted within a building in readiness for use.

Fig. 6 is an enlarged detail elevation, partly in vertical section, showing certain features of the friction-creating or braking means.

Fig. 7 is a horizontal sectional view on line 7—7 of Fig. 6.

Fig. 8 is a vertical section partly in elevation, illustrating the means for normally housing the rope.

Fig. 9 is a perspective view of the reel 55 upon which the rope is normally wound.

Fig. 10 is an elevation, illustrating the attachment connected with the fire escape, for use by painters or others who must perform work at the exterior of a building. 60

Fig. 11 is a perspective view of the attachment shown in Fig. 10.

The numerous details of construction herein disclosed, will be rather specifically described, with the understanding that 65 within the scope of the invention as claimed, variations may be made.

At 12 I have shown a substantially U-shaped frame whose arms 13 are disposed in rather closely spaced relation with each other, the lower ends 14 of said arms extending inwardly and upwardly from the arm-connecting portion 15 of the frame. This portion 15 constitutes a seat for the occupant and it is preferably reinforced 70 against downward bending, by a tie-rod 16. The upper end of this rod may be connected in any desired manner with a spacing device 17 which extends between the arms 13, above their lower portions 14. Preferably, this 80 spacing device consists of a sleeve 18 abutting the inner sides of the arms and a rivet or bolt 19 passing through said arms and sleeve. The upper ends of the arms 13 preferably curve toward each other somewhat 85 and are then curved outwardly and downwardly to provide friction shoes 20—20^a.

Front and rear plates 21 are suitably secured against the front and rear edges of the arms 13, above their portions 14, said 90 arms and plates co-operating in forming a casing C. A rope 22 enters the casing C through its open upper end and contacts with one or the other of the shoes 20—20^a, and said rope passes again out of the casing 95 against the other shoe, from which it extends downwardly as at 23.

A U-shaped friction shoe 24 is mounted in the casing C upon a transverse bolt 25, and the arms of this shoe are preferably 100 curved at their ends to contact with the two reaches of the rope 22, within said casing.

Any desired means, such as the stud 26 and the nuts 27, may be employed for spreading the arms of the shoe 24, to produce more angling of the rope reaches and hence to increase the friction. In the present showing, the ends of the stud 26 pass slidably through openings 28 in the arms of the shoe 24, and the nuts 27 contact with the inner sides of said arms. Preferably, the arm-connecting portion of the shoe 24 is bent upwardly into substantially arched form to provide an eye 29 through which the bolt 25 passes. Vertically spaced openings 30 may well be provided in the plates 21, and any of these openings may receive the bolt 25, permitting vertical adjustment of the shoe 24. Thus, the angling of the rope and the consequent friction exerted thereon, may be varied as desired.

Two rope guides 31, preferably in the form of rollers, are mounted in the casing C below the U-shaped shoe 24, and above these rope guides, a cylindrical friction shoe 32 is provided. This shoe is carried by a bolt 33 passing through it and through the plates 21, and in order that the shoe may be adjusted toward or from the guides, to vary the angling of the rope and the consequent friction, I provide the plates 21 with vertically spaced openings 34, any of which may receive said bolt 33. To hold the shoe 32 against rotation, it is provided with a projecting stud 35, receivable in one or another of the openings 34, according to the position occupied by said shoe.

The downwardly extending portion 23 of the rope 22 is held inwardly and angled below the shoe 20 or 20^a as the case may be, by means of a roller 36, said roller being carried by an arm 37 having an adjustable connection 38 with the casing C, so that said roller may be adjusted toward and from said casing to vary the angling of the rope at this point and to consequently vary the friction. There is one roller 36 and one arm 37 at each edge of the casing C, and as will be herein-after more fully explained, the rope may be engaged with one or the other of these rollers.

I mount novel friction-creating or brake means upon the portions 14 of the arms 13. As the construction associated with each of these portions 14 is the same as that associated with the other, only one construction will be described. A lever 39, preferably formed of spring steel, is disposed under the portion 14 and may be suitably fulcrumed at 40 to said portion. This lever is provided with a transversely disposed U-shaped end 41 which straddles the portion 14 and contacts with the upper side of the rope, in which connection, it will be observed that the downwardly extended portion 23 of said rope, extends along the upper side of said

portion 14. Appropriate means, such as a bolt 42, connects the lower end of the lever 39 with the lower part of the frame portion 14. By tightening this bolt, the upper arm of the U-shaped lever end 41, may be drawn downwardly against the rope portion 23, with a desired amount of force, to create the requisite friction. To prevent possible lateral swinging of the lever 39, which would permit the U-shaped end 41 to clear the rope portion 23, I preferably provide said lever 43 with an opening slidably receiving a stud 43 which is rigidly carried by the frame portion 14.

At the upper end of the lever 39, I mount a hand-controlled eccentric 44 which is so positioned as to hold the rope against possible disengagement from the U-shaped lever end 41. Upon turning in the desired manner, this eccentric is forced to angle the rope to a greater or lesser extent, to control the friction, and it will be clear from Figs. 6 and 7, that when said eccentric is turned to the required extent, the rope will be forced against the bight portion 41^a of the lever end 41, causing the latter to exert a braking action upon the rope.

In constructing the eccentric 44, I preferably make use of a single metal rod. This rod is bent to form a handle loop 45 and the ends of said rod are bent laterally in the same direction to form a pair of arms 46 and 47 at an angle to the plane of said loop, the arm 46 being of greater length than the arm 47. A sleeve 48 is passed around both of the arms 46-47 and may be of substantially flat form as shown in Fig. 7. The arm 46 projects below the sleeve 48, passes through an opening 49 in the frame portion 14, and is provided with a nut 50. Thus, the eccentric 44 is pivotally mounted.

For normally housing the rope 22, that is the portion thereof which is not normally engaged with the friction-creating means above described, I make the provision shown in Figs. 5, 8 and 9. In these views, 51 denotes a preferably cylindrical casing open at its lower end but provided at its upper end with a rigidly attached closure 52 having a central opening 53. A reel is provided, about which the rope 22 is wound, said reel consisting of a shaft 54 having a rigidly attached disk 55 at its lower end. The upper end of this shaft passes normally through the opening 53 and the disk 55 is then disposed within the open lower end of the casing 51, sufficient space however being left between said disk and the casing wall, to permit the rope to pass to the exterior of said casing and on to the rope-engaging means above described. A cotter pin 56 or the like, may be passed through the upper end of the shaft 54 to normally hold it against downward sliding from the opening 53, and I pre-

fer to provide said upper end of said shaft, with a vertical slot 57 through which one end of the rope passes loosely, this end being provided with a loop 58 while the other 5 end of said rope is formed with a suitable loop 59. This loop 59 is normally hooked over a suitable hook 60 within the building, and a pair of bails 61, secured to the plates 21, may also be engaged with this hook to 10 normally support the main body of the device in such a position as to render it readily accessible for use. Adjacent this main body of the device, the casing 51 and associated parts, may be suitably supported by means 15 of a bail 62 and a hook 63.

When the device is to be used, the casing 51 and associated parts are disconnected from the hook 63, the cotter pin 56 is withdrawn, and said container may be removed 20 from the reel of rope, or may be thrown out of the window bodily with said reel. In either instance, the rope will readily unwind from the reel and will hang out of the window. The bails 61 of the main body are 25 now disengaged from the hook 60 and the person who is to descend, will pass his legs through the lower portion of the frame 12 and will climb out of the window. His weight causes descent of the main body of 30 the device along the rope 22 and the various friction-creating devices hereinbefore described, control the rate of descent. If desired, the occupant may operate one of the eccentrics 44 to increase or diminish his 35 speed.

When one person has descended, another may pull the rope 22 upwardly, thus again elevating the main body of the device, to the floor from which the descent was made. 40 Then, the loop 59 is removed from the hook 60 and the loop 58 is engaged with said hook, so that the end of the rope having said loop 59 may be thrown out of the window. Assuming that the rope engaged the shoe 20, the 45 roller 36 and the parts 44-41, during the preceding descent, said rope will now be disengaged from these parts and will be engaged with the shoe 20, the roller 36, the eccentric 44, and the lever end 41 at the 50 opposite side of the device, for the second descent. Hence, it will be seen that the device may be advantageously used as many times as desired, in succession, it being only necessary at the proper time, to interchange 55 the loops 58-59 and to shift the rope from one side of the device to the other.

I prefer to provide means, whereby a workman, such as a painter, may make use of the fire escape when working at the exterior 60 of a building. To accomplish this, I make the provision shown in Figs. 10 and 11. In these views, 64 designates an inverted V-shaped metal rod the lower ends of said rod being bent upwardly to provide hooks

65, while the apex of said rod is bent downwardly to provide a supporting hook 66. Chains 67 are adjustably engaged with the hooks 65 and support a suitable board or the like 68 which may either constitute a seat or a foot rest for the workman. When this 70 attachment is to be used, hook 64 is passed through the bails 61 and engages with the upper end of the casing C.

The various details of construction herein disclosed, may be followed if desired, but 75 within the scope of the invention as claimed, variations may be made.

I have, in Figs. 1 and 2, indicated a chain 69 which may pass around the occupant's body if desired, to insure that he shall not 80 fall from the device. However, use of this chain in all instances, will not be necessary.

I claim:

1. In a fire escape, a substantially U-shaped frame whose arms are disposed in closely spaced relation and whose arm-connecting portion constitutes a seat, front and rear plates secured to said arms and forming therewith a casing open at its upper end, a rope passing into the casing through said 90 open end and passing again outwardly through said end, and friction-creating means in said casing engaging said rope. 95

2. A structure as specified in claim 1; the upper ends of said arms being curved laterally and downwardly to provide friction shoes, the outwardly passing rope portion being passed over one of said shoes and extending downwardly therefrom, and manually controlled brake means on one of said arms to engage said downwardly extending rope portion, the shoe of the other arm engaging the portion of the rope entering the casing. 100

3. In a fire escape, a support, a U-shaped friction shoe mounted on said support, the arms of said shoe being adapted to engage rope reaches, and means for spreading said arms to increase their friction against the rope. 105

4. In a fire escape, a support, a pair of rope guides mounted thereon in spaced relation, a cylindrical brake shoe opposite the space between said guides, a bolt connecting the shoe with the support, the latter having a plurality of openings different distances from the guides, any of which may receive said bolt, and a stud on said shoe receivable in one or another of said openings to hold the shoe against rotation. 115

5. In a fire escape, a body support frictionally connected with a supporting rope and embodying a bar portion along one side of which the rope passes, a lever fulcrumed between its ends at the other side of said bar portion and having a transverse U-shaped end which straddles said bar portion and engages the side of the rope remote there- 120
125

from, and means associated with the other end of the lever for swinging the latter about its fulcrum to vary the friction against the rope.

5. In a brake means for a fire escape, an eccentric comprising a rod bent to form a handle loop, the ends of the rod being bent laterally in the same direction from the

plane of the loop to form arms of different lengths, and a sleeve around both arms, the longer arm constituting a pivot for the eccentric.

In testimony whereof I have hereunto affixed my signature.

ZACHARIAH F. JONES.
